(57) **CLAIM**

The ornamental design for a storage box for vial bottles as shown and described.

DESCRIPTION

The patent or application file contains at least one drawing executed in color. Copies of this patent or patent application publication with color drawing(s) will be provided by the Office upon request and payment of the necessary fee.

1. Storage box for vial bottles

2. Storage box for vial bottles

Fig. 1.1 : is a Perspective view of a storage box for vial bottles showing a first embodiment of the new design.

Fig. 1.2 : is a Front view of the storage box for vial bottles shown in Fig. 1.1.

Fig. 1.3 : is a Back view of the storage box for vial bottles shown in Fig. 1.1.

Fig. 1.4 : is a Left view of the storage box for vial bottles shown in Fig. 1.1.

Fig. 1.5 : is a Top view of the storage box for vial bottles shown in Fig. 1.1.

Fig. 1.6 : is a Bottom view of the storage box for vial bottles shown in Fig. 1.1.

Fig. 2.1 : is a Perspective view of a storage box for vial bottles showing a second embodiment of the new design.

Fig. 2.2 : is a Front view of the storage box for vial bottles shown in Fig. 2.1.

Fig. 2.3 : is a Back view of the storage box for vial bottles shown in Fig. 2.1.

Fig. 2.4 : is a Left view of the storage box for vial bottles shown in Fig. 2.1.

Fig. 2.5 : is a Top view of the storage box for vial bottles shown in Fig. 2.1.

Fig. 2.6 : is a Bottom view of the storage box for vial bottles shown in Fig. 2.1.

(Continued)

Designs 1 & 2: This is a product which is configured such that vial bottles are stored inside the present design for use.
